10 Claims

ABSTRACT OF THE DISCLOSURE

There are disclosed herein steroidal lactones of 4-hydroxy-2-butenoic acid in which the lactone ring is attached in position 3 to the 17 α -position of the steroid, with the steroids being selected from 3,17 β -dihydroxyestra-1,3-5(10)-trienes, 3,17 β -dihydroxyestra-1,3,5(10),6,8-pentaenes and 3,17 β -dihydroxy-7 α ,8-epoxyestra-1,3,5(10)-trienes. The 3-hydroxy group on the steroid nucleus may also carry an acyl substituent containing from 2 to 4 carbon atoms, an alkyl substituent containing from 1 to 4 carbon atoms or a cycloalkyl substituent containing from 5 to 6 carbon atoms. The process for preparing the steroidal lactones of this invention comprises treating the corresponding 17 α -furyl-substituted steroids with an organic peracid in the presence of a nucleophilic reagent, thus obtaining as intermediates the corresponding steroidal 4,4-dihydroxy-2-butenoic acid lactones, in which the 4-hydroxy group may be acylated, if desired. Treatment of said intermediates with sodium borohydrides yields the steroidal lactones of this invention. Said last-named compounds are highly active estrogens and methods for their use are also disclosed.

BACKGROUND OF THE INVENTION

This invention relates to steroid lactones comprising a 4-hydroxy-2-butenoic acid lactone joined to the C-17 position of a steroid nucleus to intermediates used in their preparation, and to processes for preparing the lactones of this invention.

The lactones of this invention are potent estrogens substantially free from side effects when administered orally or subcutaneously. The high oral potency of these lactones allows them to be used therapeutically in more sparing amounts than the corresponding natural estrogen from which they may be derived.

SUMMARY OF THE INVENTION

The steroid lactones of this invention are represented by Formula I,

in which Q represents the rings A, B, and C of a steroid nucleus of the estrane or the androstane series together with the substituents attached thereto.

2

More particularly, the preferred embodiment of this invention relates to compounds of Formula I in which Q represents the rings A, B, and C of a 3-substituted estrane nucleus. Such compounds are represented by general Formulae II, III and IV.

in which R represents a hydrogen atom, an alkyl group containing from one to four carbon atoms, a cycloalkyl group containing from five to six carbon atoms or an acyl group containing from two to four carbon atoms.

DETAILED DESCRIPTION OF THE INVENTION

The steroid lactones of this invention of general Formulae II, III, and IV possess estrogenic activity. More particularly, these steroid lactones exhibit potent oral activity when tested in standard laboratory tests for estrogenic activity, such as, for example the Allen Doisy test described by C. W. Emmens in "Hormone Assay," Academic Press, New York 1955, p. 401. This high degree of estrogenic activity readily distinguishes the compounds of this invention from the steroid lactones described in my co-pending U.S. application S.N. 629,358, now U.S. Patent No. 3,431,258, which are isomeric with respect to the point of attachment of the lactone portion thereof.

When these steroid lactones are employed as estrogenic agents in warm-blooded mammals, for example, rats, they may be administered alone or in dosage forms combined with pharmaceutically acceptable excipients. The proportion of the excipients used is determined by the solubility and chemical nature of the compound, chosen route of administration and standard biological practice. For example, they may be administered orally in solid form containing such excipients as starch, milk sugar, certain types of clay and so forth. They may also be administered orally in the form of solution or suspensions or they may be injected parenterally. For parenteral administration they may be used in the form of a sterile solution containing other solutes, for example, enough saline or glucose to make the solution isotonic.

The dosage of the present therapeutic agents will vary with the form of administration and the particular compound chosen. Furthermore, it will vary with the particular host under treatment. Generally, treatment is initiated with small dosages substantially less than the optimum dose of the compound. Thereafter, the dosage is increased by small increments until the optimum effect under the circumstances is reached. In general, the compounds of this invention are most desirably administered at a concentration level that will generally afford effective results without causing any harmful or deleterious side effects and preferably at a level that is in a range of from about 0.5 mcg. to about 500 mcg. per kilo per day, although as aforementioned variations will occur. However, a dosage level that is in the range of from about 5 mcg. to about 100 mcg. per kilo per day is most satisfactory. Such doses may be administered once or twice a day as required.

The preferred process for preparing the steroid lactones of general Formulae II, III, and IV may be schematically represented by Formulae V→VI→I in which Q represents rings A, B, and C of the steroid lactones II to IV as defined above and R' represents a hydrogen atom or an acyl group containing from two to four carbon atoms, such as, for example, an acetyl group, with the limitation that when R of the steroid nucleus Q is hydrogen, R¹ must also be hydrogen.

The 17α -[3'-furyl]- 17β -hydroxy steroids represented by general Formula V in which Q represents rings A, B and C of the steroid lactones II and III as defined above are the preferred starting materials for the preparation of the steroid lactones of this invention of general Formulae II and III, respectively. These starting materials are described in U.S. Pat. No. 3,271,392.

The 17α -[3'-furyl]- 17β -hydroxy steroids represented by general Formula V in which Q represents rings A, B, and C of the steroid lactone IV as defined above are the preferred starting materials for the preparation of the steroid lactones of this invention of General Formula IV defined above. These starting materials are prepared by treating the appropriate 3-alkyl or 3-cycloalkyl ethers of equilin, or the 3-tetrahydropyranyl ether of equilin with a

peracid, preferably, m-chloroperbenzoic acid, described by L. F. Fieser and M. Fieser, "Reagents for Organic Synthesis," John Wiley and Sons, New York, 1967, p. 135, in an inert solvent, preferably chloroform, isolating the product—the corresponding $7\alpha,8$ -epoxy derivative—and treating said product with 3-furyllithium in a mixture of ether-toluene at room temperature in the manner described in U.S. Pat. No. 3,271,392. In this manner, the corresponding 3-alkyl and 3-cycloalkyl ethers of general Formula V, the desired starting materials of Formula V in which Q represents rings A, B, and C of the steroid lactone IV in which R represents an alkyl or a cycloalkyl group are obtained, as well as the corresponding 3-tetrahydropyranyl ether of $7\alpha,8$ -epoxy- 17α -[3'-furyl]estera-1,3,5(10)-triene-3,17-diol. The latter compound is hydrolyzed under mildly acidic conditions, for example, dilute hydrochloric acid in methanol, to yield the corresponding free 3-hydroxy derivative of Formula V in which Q represents rings A, B, and C of the steroid lactone IV in which R represents hydrogen, which together with its corresponding 3-acyl derivatives are the remaining preferred starting materials of Formula V. Said 3-acyl derivatives are readily prepared by treating the above 3-hydroxy derivative of Formula V with an appropriate acid anhydride or acid halide in pyridine at room temperature.

In the preceding process for the preparation of said starting materials of general Formula V in which Q represents rings A, B, and C of steroid lactone IV and R represents a hydrogen atom or an acyl group, the tetrahydropyranyl ether of equilin is preferably used rather than equilin. This preference is based on my observation that, when equilin is used in this process, the consequential presence of the free 3-hydroxy group during the treatment with the reagent, 3-furyllithium, allows a complex to be formed between the reagent and the hydroxy group causing a waste of the reagent and adversely affecting the yield of the process.

The 3-alkyl and 3-cycloalkyl ethers of equilin, used for the preparation of the above starting materials, are prepared from equilin according to the methods described by F. Glockling and D. Kingston, Chemistry and Industry, 1037 (1961) and the 3-tetrahydropyranyl ether of equilin is prepared according to the method of A. D. Cross et al., Steroids, vol. 4, 423 (1964). Equilin is a well-known naturally occurring steroid, see L. F. Fieser and M. Fieser, "Steroids," Reinhold Publishing Corporation, New York, 1959. 3-furyllithium is prepared according to the method of S. Gronowitz and G. Sorlin, Arkiv for Kemi, vol. 19, 515 (1962), by the action of butyllithium upon 3-iodofuran, in ether at -60° C. In turn, 3-iodofuran is obtained from furoic acid according to the method of G. Wright and H. Gilman, J. Am. Chem. Soc., vol. 55, 3302 (1933).

The above starting materials of Formula V are converted to the intermediates of Formula VI, in which Q represents rings A, B, and C of the steroid lactones II, III, and IV in which R represents a hydrogen atom or an alkyl, cycloalkyl or acyl group defined as above, and R' represents hydrogen, by treatment with an organic peracid in the presence of a nucleophilic reagent such as acetic acid or water. Preferably, a buffer, such as sodium acetate, is employed during the course of the reaction and approximately the same molar amounts of nucleophilic reagent and steroid starting material are employed. Among the organic peracids capable of being employed in this process, I have obtained very good results with m-chloroperbenzoic acid used in a two to ten fold excess. Any practical solvent inert to the reaction conditions may be employed; chloroform is quite suitable for this purpose. Preferred ranges for reaction time and temperature are from one half to twenty-four hours and 20 – 30° C., respectively.

The corresponding acylates of the above intermediates, the compounds of Formula VI in which Q is as defined above and R' is an acylate as defined above, are readily

prepared by treatment with the appropriate aliphatic acid anhydride or acyl halide in the presence of pyridine. If a free hydroxy group should also be present at the 3-position of the steroid nucleus, it also will be acylated during this reaction.

Alternatively, the intermediates of Formula VI, in which Q represents ring A, B, and C of the steroid lactone IV in which R is as defined above may be prepared directly from 17α -[3'-furyl]estra-1,3,5(10),7-tetraene-3,17-diol and its corresponding 3-alkyl, 3-cycloalkyl or 3-acyl derivatives, described in U.S. Patent No. 3,271,392, by treatment with an organic peracid as described above.

Finally, the intermediates of general Formula VI, in which Q is defined as above and R' represents a hydrogen atom or an acyl group as defined above, are treated with sodium borohydride to yield the steroid lactones of this invention of general Formula II, III and IV in which R represents a hydrogen atom, an alkyl group or a cycloalkyl group as defined above. Although this reaction may be accomplished by using a variety of conventional conditions such as those described by N. G. Gaylord, Interscience Publications, New York, 1956, pp. 100-102, I have found that excellent yields are obtained by employing a 10 to 50 fold molar excess of sodium borohydride, in methanol solution. A preferred range for reaction time is from 30 minutes to three hours and a preferred range of reaction temperature is from 20 to 30° C. The product is isolated by conventional means, usually the methanol is evaporated from the reaction mixture, the residue is taken up in water, acidified by the addition of an acid, preferably 10 percent hydrochloric acid and extracted with ether. After evaporation of the extract, crystallization or chromatography is used to purify the product. During the course of this reaction, a 3-acyl group, if present, will be removed affording the corresponding 3-hydroxy derivative.

The steroid lactones of this invention of Formulae II, III, and IV in which R is an acyl group, as defined above, are readily obtained from the corresponding steroid lactone of Formulae II, III or IV in which R is hydrogen, prepared as described above, on treatment with the appropriate aliphatic acyl anhydride or acyl chloride in pyridine solution.

The following examples will illustrate this invention.

Example 1

The higher ether homologues of equilin are prepared by the method of F. Glockling and D. Kingston, described in Chem. and Ind., 1037 (1961), by the action of the corresponding alkyl halides on the sodium or potassium salts of the phenols. Accordingly, equilin 3-methyl ether, equilin 3-ethyl ether, equilin 3-propyl ether, equilin 3-isopropyl ether, equilin 3-n-butyl ether, equilin 3-sec.-butyl ether, equilin 3-cyclopentyl ether, and equilin 3-cyclohexyl ether are obtained. The corresponding tetrahydropyranyl ether is prepared according to the method described by A. D. Cross et al. in Steroids, vol. 4, p. 423 (1964).

Example 2

m-Chloroperbenzoic acid (4.05 g.) is added by portions, over a period of 30 minutes, to a stirred, ice-cold solution of equilin 3-methyl ether (5 g.). The mixture is stirred for an additional 2 hours in the ice-bath and then for 30 minutes at room temperature. The solution is washed with a 5% sodium carbonate solution and with water, dried and evaporated. The colour is removed from the crude crystalline product by filtration through a column of alumina. The fractions eluted with 1:1 benzene-petroleum ether are combined and crystallized from methanol to yield 7α ,8-epoxy-3-methoxyestra-1,3,5(10)-trien-17-one, M.P. 176-178° C.

In the same manner, the other ethers of equilin, obtained in Example 1 are oxidized to the corresponding 7α ,8-epoxy derivatives, when treated with m-chloroperbenzoic acid in chloroform solution. In this manner there are obtained:

- 7 α ,8-epoxy-3-ethoxyestra-1,3,5(10)-trien-17-one,
7 α ,8-epoxy-3-propoxyestra-1,3,5(10)-trien-17-one,
7 α ,8-epoxy-3-isopropoxyestra-1,3,5(10)-trien-17-one,
3-n-butoxy-7 α ,8-epoxyestra-1,3,5(10)-trien-17-one,
5 3-sec.-butoxy-7 α ,8-epoxyestra-1,3,5(10)-trien-17-one,
3-cyclopentylxyloxy-7 α ,8-epoxyestra-1,3,5(10)-trien-17-one,
3-cyclohexyloxy-7 α ,8-epoxyestra-1,3,5(10)-trien-17-one
10 and
7 α ,8-epoxy-3-tetrahydropyranylxyloxyestra-1,3,5(10)-trien-17-one.

Example 3

A solution of 3-iodofuran (5 g.), ether (100 ml.), and a 1.47 N ethereal solution of n-butyllithium (13.6 ml.), is stirred at -60° C. for 30 minutes. A solution of 7 α ,8-epoxy-3-methoxyestra-1,3,5(10)-trien-17-one (5 g.), obtained in Example 2, in toluene (200 ml.), is then added and the mixture is stirred at room temperature for 16 hours. Ether and water are added. The organic phase is separated and further washed with water. After drying and evaporating the solvents, the solid residue is crystallized several times with methylene chloride-ether to give the 3-alkyl ether, 7 α ,8-epoxy-17 α -[3'-furyl]-3-methoxyestra-1,3,5(10)-trien-17-ol, M.P. 223-225° C.

In the same manner, the other 3-alkyl ethers of 7 α ,8-epoxy-3-hydroxyestra-1,3,5(10)-trien-17-one, prepared as described in Example 2, are treated with 3-furyllithium to yield the corresponding 17 α -[3'-furyl]-17 β -hydroxy derivatives such as:

- 30 7 α ,8-epoxy-3-ethoxy-17 α -[3'-furyl]estra-1,3,5(10)-trien-17-ol,
7 α ,8-epoxy-17 α -[3'-furyl]-3-propoxyestra-1,3,5(10)-trien-17-ol,
7 α ,8-epoxy-17 α -[3'-furyl]-3-isopropoxyestra-1,3,5(10)-trien-17-ol,
35 3-n-butoxy-7 α ,8-epoxy-17 α -[3'-furyl]estra-1,3,5(10)-trien-17-ol,
3-sec.-butoxy-7 α ,8-epoxy-17 α -[3'-furyl]estra-1,3,5(10)-trien-17-ol,
40 3-cyclopentylxyloxy-7 α ,8-epoxy-17 α -[3'-furyl]estra-1,3,5(10)-trien-17-ol,
3-cyclohexyloxy-7 α ,8-epoxy-17 α -[3'-furyl]estra-1,3,5(10)-trien-17-ol and,
7 α ,8-epoxy-17 α -[3'-furyl]-3-tetrahydropyranylxyloxyestra-1,3,5(10)-trien-17-ol.

Example 4

A solution of 7 α ,8-epoxy-17 α -[3'-furyl]-3-tetrahydropyranylxyestra-1,3,5(10)-trien-17-ol (31.1 g.), obtained as described in Example 3, in methanol (1244 ml.), is stirred for one hour at room temperature with a 0.1 N solution of hydrochloric acid (311 ml.). Water (1800 ml.) is added and the resulting solid is filtered, washed well with water and dried. Several crystallizations of this solid from nitromethane yields 7 α ,8-epoxy-17 α -[3'-furyl]estra-1,3,5(10)-trien-3,17-diol, M.P. 154-156° C.

Example 5

A solution of 7 α ,8-epoxy-17 α -[3'-furyl]estra-1,3,5(10)-trien-3,17-diol, (5 g.), obtained in Example 4, in pyridine (50 ml.), and acetic anhydride (50 ml.), is stirred at room temperature for 2½ hours. The solution is diluted with ice-water and is extracted with ether. The ether is washed with dilute sulfuric acid, water, sodium bicarbonate, and water, again to neutrality. The solution is dried and evaporated to yield 3-acetoxy-7 α ,8-epoxy-17 α -[3'-furyl]estra-1,3,5(10)-trien-17-ol as an amorphous solid,
 CHCl_3 1750 cm^{-1} (acetate) and 875 cm^{-1} (furan group)

70 In the same manner, but using an equivalent amount of propionic or butyric anhydride instead of acetic anhydride, 7 α ,8-epoxy-17 α -[3'-furyl]-3-propionyloxyestra-1,3,5(10)-trien-17-ol and 3-butanoyloxy-7 α ,8-epoxy-17 α -[3'-furyl]estra-1,3,5(10)-trien-17-ol, are obtained, respectively.

A mixture of the 17α -[3'-furyl]- 17β -hydroxy steroid, 17α -[3'-furyl]-3-methoxyestra-1,3,5(10)-trien-17-ol (17 g.), described in U.S. Pat. No. 3,271,392, chloroform (850 ml.), sodium acetate (17 g.), acetic acid (17 ml.) and m-chloroperbenzoic acid (85%) (23.65 g.) is stirred at room temperature for 1 hour. Ether is added. The organic solution is washed with sodium bicarbonate and water, dried and evaporated. The residue is chromatographed on silica gel. The fractions eluted with 2% benzene in methanol are combined and crystallized with acetone-hexane to give the intermediate of Formula VI, 4,4-dihydroxy-3-[17 β -hydroxy-3'-methoxyestra-1',3',5'(10')-trien-17'-yl]-2-butenoic acid lactone, M.P. 214-216° C. $[\alpha]_D^{CHCl_3} = +81.9^\circ$.

In the same manner, the appropriate 17α -[3'-furyl]- 17β -hydroxy steroids, described in U.S. Pat. No. 3,271,392, are oxidized to the corresponding intermediates of Formula VI, when treated with m-chloroperbenzoic acid. In this manner, there are obtained the corresponding intermediates of Formula VI:

4,4-dihydroxy-3-[3',17 β -dihydroxyestra-1',3',5'(10')-trien-17'-yl]-2-butenoic acid lactone,
 3-[3'-ethoxy-17 β -hydroxyestra-1',3',5'(10')-trien-17'-yl]-4,4-dihydroxy-2-butenoic acid lactone,
 4,4-dihydroxy-3-[17 β -hydroxy-3'-propoxyestra-1',3',5'(10')-trien-17'-yl]-2-butenoic acid lactone,
 4,4-dihydroxy-3-[17 β -hydroxy-3'-isopropoxyestra-1',3',5'(10')-trien-17'-yl]-2-butenoic acid lactone,
 3-[3'-n-butoxy-17 β -hydroxyestra-1',3',5'(10')-trien-17'-yl]-4,4-dihydroxy-2-butenoic acid lactone,
 3-[3'-sec-butoxy-17 β -hydroxyestra-1',3',5'(10')-trien-17'-yl]-4,4-dihydroxy-2-butenoic acid lactone,
 3-[3'-cyclopentyloxy-17 β -hydroxyestra-1',3',5'(10')-trien-17'-yl]-4,4-dihydroxy-2-butenoic acid lactone, M.P. 194.5-196°, $[\alpha]_D^{CHCl_3} = +46.9^\circ$,
 3-[3'-cyclohexyloxy-17 β -hydroxyestra-1',3',5'(10')-trien-17'-yl]-4,4-dihydroxy-2-butenoic acid lactone,
 3-[3'-acetoxy-17 β -hydroxyestra-1',3',5'(10')-trien-17'-yl]-4,4-dihydroxy-2-butenoic acid lactone, M.P. 230-233° $[\alpha]_D^{CHCl_3} = +117^\circ$,
 4,4-dihydroxy-3-[17 β -hydroxy-3'-propionyloxyestra-1',3',5'(10')-trien-17'-yl]-2-butenoic acid lactone,
 3-[3'-n-butanoyloxy-17 β -hydroxyestra-1',3',5'(10')-trien-17'-yl]-4,4-dihydroxy-2-butenoic acid lactone,
 4,4-dihydroxy-3-[3',17 β -dihydroxyestra-1',3',5'(10'),6',8'-pentaen-17'-yl]-2-butenoic acid lactone,
 4,4-dihydroxy-3-[17 β -hydroxy-3'-isopropoxyestra-1',3',5'(10'),6',8'-pentaen-17'-yl]-2-butenoic acid lactone,
 3-[3'-n-butoxy-17 β -hydroxyestra-1',3',5'(10'),6',8'-pentaen-17'-yl]-4,4-dihydroxy-2-butenoic acid lactone,
 3-[3'-sec-butoxy-17 β -hydroxyestra-1',3',5'(10'),6',8'-pentaen-17'-yl]-4,4-dihydroxy-2-butenoic acid lactone,
 3-[3'-cyclopentyloxy-17 β -hydroxyestra-1',3',5'(10'),6',8'-pentaen-17'-yl]-4,4-dihydroxy-2-butenoic acid lactone,
 3-[3'-cyclohexyloxy-17 β -hydroxyestra-1',3',5'(10'),6',8'-pentaen-17'-yl]-4,4-dihydroxy-2-butenoic acid lactone,
 3-[3'-acetoxy-17 β -hydroxyestra-1',3',5'(10'),6',8'-pentaen-17'-yl]-4,4-dihydroxy-2-butenoic acid lactone, and
 3-[3'-n-butanoyloxy-17 β -hydroxyestra-1',3',5'(10'),6',8'-pentaen-17'-yl]-4,4-dihydroxy-2-butenoic acid lactone.

(B) A solution of m-chloroperbenzoic acid (70%—7.7 g.) in chloroform (100 ml.) is added to a mixture of

$7\alpha,8$ -epoxy- 17α -[3'-furyl]-3-methoxyestra-1,3,5(10)-trien-17-ol (5.0 g.), prepared as described in Example 3, chloroform (100 ml.), sodium acetate (5.0 g.) and acetic acid (5.0 ml.). The reaction mixture is stirred for 50 minutes. Ether is added and the organic solution is washed with sodium bicarbonate and water, dried and evaporated. The residue is suspended in ether and the insoluble material collected affording $3-[7\alpha,8$ -epoxy- 17β -hydroxy-3'-methoxyestra-1',3',5'(10')-trien-17'-yl]-4,4-dihydroxy-2-butenoic acid lactone, M.P. 235-236° C., $[\alpha]_D^{CHCl_3} = +105.1^\circ$.

In the same manner, $7\alpha,8$ -epoxy- 17α -[3'-furyl]estra-1,3,5(10)-trien-3,17-diol, prepared as described in Example 4, the appropriate 3-alkyl and 3-cycloalkyl ethers, prepared as described in Example 3, and the appropriate 3-acyl derivatives, prepared as described in Example 5, are oxidized with m-chloroperbenzoic acid. In this manner, there are obtained the corresponding intermediates of Formula VI:

- 20 3-[7 $\alpha,8$ -epoxy-3',17 β -dihydroxyestra-1',3',5'(10')-trien-17'-yl]-4,4-dihydroxy-2-butenoic acid lactone,
 3-[17 $\alpha,8$ -epoxy-3'-ethoxy-17 β -hydroxyestra-1',3',5'(10')-trien-17'-yl]-4,4-dihydroxy-2-butenoic acid lactone,
 25 3-[17 $\alpha,8$ -epoxy-17 β -hydroxy-3'-propoxyestra-1',3',5'(10')-trien-17'-yl]-4,4-dihydroxy-2-butenoic acid lactone,
 3-[7 $\alpha,8$ -epoxy-17 β -hydroxy-3'-isopropoxyestra-1',3',5'(10')-trien-7'-yl]-4,4-dihydroxy-2-butenoic acid lactone,
 30 3-[3'-n-butoxy-7 $\alpha,8$ -epoxy-17 β -hydroxyestra-1',3',5'(10')-trien-17'-yl]-4,4-dihydroxy-2-butenoic acid lactone,
 3-[3'-sec-butoxy-7 $\alpha,8$ -epoxy-17 β -hydroxyestra-1',3',5'(10')-trien-17'-yl]-4,4-dihydroxy-2-butenoic acid lactone,
 35 3-[3'-cyclopentyloxy-7 $\alpha,8$ -epoxy-17 β -hydroxyestra-1',3',5'(10')-trien-17'-yl]-4,4-dihydroxy-2-butenoic acid lactone, M.P. 235-237° C. $[\alpha]_D^{CHCl_3} = +93.4^\circ$,
 3-[3'-cyclohexyloxy-7 $\alpha,8$ -epoxy-17 β -hydroxyestra-1',3',5'(10')-trien-17'-yl]-4,4-dihydroxy-2-butenoic acid lactone, and
 40 3-[3'-acetoxy-7 $\alpha,8$ -epoxy-17 β -hydroxyestra-1',3',5'(10')-trien-17'-yl]-4,4-dihydroxy-2-butenoic acid lactone,
 3-[7 $\alpha,8$ -epoxy-17 β -hydroxy-3'-propionyloxyestra-1',3',5'(10')-trien-17'-yl]-4,4-dihydroxy-2-butenoic acid lactone, and
 45 3-[3'-n-butanoyloxy-7 $\alpha,8$ -epoxy-17 β -hydroxyestra-1',3',5'(10')-trien-17'-yl]-4,4-dihydroxy-2-butenoic acid lactone.

In the same manner, 17α -[3'-furyl]estra-1,3,5(10),7-tetraen-3,17-diol, its appropriate corresponding 3-alkyl and 3-cycloalkyl ether and its appropriate corresponding 3-acyl derivatives, prepared as described in U.S. Pat. No. 3,271,392 are oxidized with m-chloroperbenzoic acid to the corresponding intermediates of Formula VI described above.

Example 7

- 60 A solution of the intermediate of Formula VI, 4,4-dihydroxy-3-[17 β -hydroxy-3'-methoxyestra-1',3',5'(10')-trien-17'-yl]-2-butenoic acid lactone, prepared as described in Example 6, 5.8 g., in pyridine (50 ml.), and acetic anhydride (50 ml.) is stirred at room temperature for three hours. The reaction mixture is diluted with water and extracted with chloroform. The chloroform extract is washed with dilute sulfuric acid, water, sodium bicarbonate solution, and water, dried over sodium sulfate, filtered and evaporated to dryness. The residue is subjected to chromatography on silica gel. Elution with 25% ethyl acetate in benzene affords the corresponds acetylated intermediate of Formula VI, 4-acetoxy-4-hydroxy-3-[17 β -hydroxy-3'-methoxyestra-1',3',5'(10')-trien-17'-yl]-2-butenoic acid lactone, which is purified by recrystalliza-

tion from methanol to yield crystals, M.P. 206-209° C., $[\alpha]_D^{CHCl_3} + 129^\circ$.

In the same manner, the remaining intermediates of Formula VI, prepared as described in Example 6, are acetylated to yield the corresponding acetylated intermediates of Formula VI. In this manner there are obtained the following corresponding acetylated intermediate of Formula VI:

- 4-acetoxy-3-[3'-acetoxy-17' β -hydroxyestra-1',3',5'(10')-trien-17'-yl]-4-hydroxy-2-butenoic acid lactone, M.P. 224-26° $[\alpha]_D^{CHCl_3} = + 117.3^\circ$,
 4-acetoxy-3-[3'-ethoxy-17' β -hydroxyestra-1',3',5'(10')-trien-17'-yl]-4-hydroxy-2-butenoic acid lactone,
 4-acetoxy-4-hydroxy-3-[17' β -hydroxy-3'-propoxyestra-1',3',5'(10')-trien-17'-yl]-2-butenoic acid lactone,
 4-acetoxy-4-hydroxy-3-[17' β -hydroxy-3'-isopropoxyestra-1',3',5'(10')-trien-17'-yl]-2-butenoic acid lactone,
 4-acetoxy-3-[3'-n-butoxy-17' β -hydroxyestra-1',3',5'(10')-trien-17'-yl]-4-hydroxy-2-butenoic acid lactone,
 4-acetoxy-3-[3'-sec.-butoxy-17' β -hydroxyestra-1',3',5'(10')-trien-17'-yl]-4-hydroxy-2-butenoic acid lactone,
 4-acetoxy-3-[3'-cyclopentyloxy-17' β -hydroxyestra-1',3',5'(10')-trien-17'-yl]-4-hydroxy-2-butenoic acid lactone,
 4-acetoxy-3-[3'-cyclohexyloxy-17' β -hydroxyestra-1',3',5'(10')-trien-17'-yl]-4-hydroxy-2-butenoic acid lactone,
 4-acetoxy-4-hydroxy-3-[17' β -hydroxy-3'-propionyloxyestra-1',3',5'(10')-trien-17'-yl]-2-butenoic acid lactone,
 4-acetoxy-3-[3'-n-butanoyloxy-17' β -hydroxyestra-1',3',5'(10')-trien-17'-yl]-4-hydroxy-2-butenoic acid lactone,
 4-acetoxy-3-[3'-acetoxy-17' β -hydroxyestra-1',3',5'(10')-6',8'-pentaen-17'-yl]-4-hydroxy-2-butenoic acid lactone,
 4-acetoxy-4-hydroxy-3-[17' β -hydroxy-3'-methoxyestra-1',3',5'(10'),6',8'-pentaen-17'-yl]-2-butenoic acid lactone,
 4-acetoxy-3-[3'-ethoxy-17' β -hydroxyestra-1',3',5'(10'),6',8'-pentaen-17'-yl]-4-hydroxy-2-butenoic acid lactone,
 4-acetoxy-4-hydroxy-3-[17' β -hydroxy-3'-propoxyestra-1',3',5'(10'),6',8'-pentaen-17'-yl]-2-butenoic acid lactone,
 4-acetoxy-4-hydroxy-3-[17' β -hydroxy-3'-isopropoxyestra-1',3',5'(10'),6',8'-pentaen-17'-yl]-2-butenoic acid lactone,
 4-acetoxy-[3'-n-butoxy-17' β -hydroxyestra-1',3',5'(10'),6',8'-pentaen-17'-yl]-4-hydroxy-2-butenoic acid lactone,
 4-acetoxy-[3'-sec.-butoxy-17' β -hydroxyestra-1',3',5'(10'),6',8'-pentaen-17'-yl]-4-hydroxy-2-butenoic acid lactone,
 4-acetoxy-[3'-cyclopentyloxy-17' β -hydroxyestra-1',3',5'(10'),6',8'-pentaen-17'-yl]-4-hydroxy-2-butenoic acid lactone,
 4-acetoxy-[3'-cyclohexyloxy-17' β -hydroxyestra-1',3',5'(10'),6',8'-pentaen-17'-yl]-4-hydroxy-2-butenoic acid lactone,
 4-acetoxy-4-hydroxy-3-[17' β -hydroxy-3'-propionyloxyestra-1',3',5'(10'),6',8'-pentaen-17'-yl]-2-butenoic acid lactone,
 4-acetoxy-3-[3'-n-butanoyloxy-17' β -hydroxyestra-1',3',5'(10'),6',8'-pentaen-17'-yl]-4-hydroxy-2-butenoic acid lactone,

- 4-acetoxy-3-[7' α ,8'-epoxy-17' β -hydroxy-3'-propoxyestra-1',3',5'(10')-trien-17'-yl]-4-hydroxy-2-butenoic acid lactone,
 4-acetoxy-3-[7' α ,8'-epoxy-17' β -hydroxy-3'-isopropoxyestra-1',3',5'(10')-trien-17'-yl]-4-hydroxy-2-butenoic acid lactone,
 4-acetoxy-3-[3'-n-butoxy-7' α ,8'-epoxy-17' β -hydroxyestra-1',3',5'(10')-trien-17'-yl]-4-hydroxy-2-butenoic acid lactone,
 10 4-acetoxy-3-[3'-sec.-butoxy-7' α ,8'-epoxy-17' β -hydroxyestra-1',3',5'(10')-trien-17'-yl]-4-hydroxy-2-butenoic acid lactone,
 4-acetoxy-3-[3'-cyclopentyloxy-7' α ,8'-epoxy-17' β -hydroxyestra-1',3',5'(10')-trien-17'-yl]-4-hydroxy-2-butenoic acid lactone,
 15 4-acetoxy-3-[3'-cyclohexyloxy-7' α ,8'-epoxy-17' β -hydroxyestra-1',3',5'(10')-trien-17'-yl]-4-hydroxy-2-butenoic acid lactone,
 4-acetoxy-3-[7' α ,8'-epoxy-17' β -hydroxy-3'-propionyloxyestra-1',3',5'(10')-trien-17'-yl]-4-hydroxy-2-butenoic acid lactone,
 20 4-acetoxy-3-[3'-n-butanoyloxy-7' α ,8'-epoxy-17' β -hydroxyestra-1',3',5'(10')-trien-17'-yl]-4-hydroxy-2-butenoic acid lactone,
 25 Example 8

(A) Sodium borohydride (16 g.) is added portionwise to a solution of the intermediate of Formula VI, 3-[3'-cyclopentyloxy-17' β -hydroxyestra-1',3',5'(10')-trien-17'-yl]-4,4-dihydroxy-2-butenoic acid lactone (8 g.), prepared as described in Example 6, in methanol (320 ml.). After 20 minutes the methanol is removed under reduced pressure. The residue is dissolved in water and the resultant solution is extracted with ether. The aqueous phase is separated and acidified with 10% sulfuric acid solution. The mixture is extracted with ether. The ether extract is washed with water, dried and evaporated. The residue is recrystallized twice from methanol and then from acetone-hexane yielding 3-[3'-cyclopentyloxy-17' β -hydroxyestra-1',3',5'(10')-trien-17'-yl]-4-hydroxy-2-butenoic acid lactone, M.P. 204-205° C.,

$$[\alpha]_D^{CHCl_3} + 70.6^\circ$$

In the same manner, 4,4-dihydroxy-3-[3',17 β -dihydroxyestra-1',3',5'(10')-trien-17'-yl]-2-butenoic acid lactone, 3-[3'-acetoxy-17' β -hydroxyestra-1',3',5'(10')-trien-17'-yl]-4,4-dihydroxy-2-butenoic acid lactone, 4,4-dihydroxy-3-[17' β -hydroxy-3'-propionyloxyestra-1',3',5'(10')-trien-17'-yl]-2-butenoic acid lactone and 3-[3'-n-butanoyloxy-17' β -hydroxyestra-1',3',5'(10')-trien-17'-yl]-4,4-dihydroxy-2-butenoic acid lactone, prepared as described in Example 6, are reduced with sodium borohydride to the steroid lactone, 4-hydroxy-3-[3',17 β -dihydroxyestra-1',3',5'(10')-trien-17'-yl]-2-butenoic acid lactone,

In the same manner, 4,4-dihydroxy-3-[3',17 β -dihydroxyestra-1',3',5'(10'),6',8'-pentaen-17'-yl]-2-butenoic acid lactone, 3-[3'-acetoxy-17' β -hydroxyestra-1',3',5'(10'),6',8'-pentaen-17'-yl]-2-butenoic acid lactone, 4,4-dihydroxy-3-[17' β -hydroxy-3'-propionyloxyestra-1',3',5'(10'),6',8'-pentaen-17'-yl]-2-butenoic acid lactone, 3-[3'-n-butanoyloxy-17' β -hydroxyestra-1',3',5'(10'),6',8'-pentaen-17'-yl]-2-butenoic acid lactone, prepared as described in Example 6, are reduced with sodium borohydride to the steroid lactone, 4-hydroxy-3-[3',17 β -dihydroxyestra-1',3',5'(10'),6',8'-pentaen-17'-yl]-2-butenoic acid lactone.

In the same manner, the appropriate intermediates of Formula VI, prepared as described in Example 6, are reduced with sodium borohydride to the corresponding steroid lactones of Formulae II and III. In this manner, there are obtained the following steroid lactones of Formulae II and III:

4-hydroxy-3-[17' β -hydroxy-3'-methoxyestra-1',3',5' (10')-trien-17'-yl]-2-butenoic acid lactone,
 3-[3'-ethoxy-17' β -hydroxyestra-1',3',5'(10')-trien-17'-yl]-4-hydroxy-2-butenoic acid lactone,
 4-hydroxy-3-[17' β -hydroxy-3'-propoxyestra-1',3',5' (10')-trien-17'-yl]-2-butenoic acid lactone,
 4-hydroxy-3-[17' β -hydroxy-3'-isopropoxyestra-1',3',5' (10')-trien-17'-yl]-2-butenoic acid lactone,
 3-[3'-n-butoxy-17' β -hydroxyestra-1',3',5'(10')-trien-17'-yl]-4-hydroxy-2-butenoic acid lactone,
 3-[3'-sec.-butoxy-17' β -hydroxyestra-1',3',5'(10')-trien-17'-yl]-4-hydroxy-2-butenoic acid lactone,
 3-[3'-cyclohexyloxy-17' β -hydroxyestra-1',3',5'(10')-trien-17'-yl]-4-hydroxy-2-butenoic acid lactone,
 4-hydroxy-3-[17' β -hydroxy-3'-methoxyestra-1',3',5'(10'),6',8'-pentaen-17'-yl]-2-butenoic acid lactone,
 4-hydroxy-3-[3'-ethoxy-17' β -hydroxyestra-1',3',5'(10'),6',8'-17'-yl]-2-butenoic acid lactone,
 4-hydroxy-3[17' β -hydroxy-3'-propoxyestra-1',3',5'(10'),6',8'-17'-yl]-2-butenoic acid lactone,
 4-hydroxy-3-[17' β -hydroxy-3'-isopropoxyestra-1',3',5' (10'),6',8'-17'-yl]-2-butenoic acid lactone,
 3-[3'-n-butoxy-17' β -hydroxyestra-1',3',5'(10'),6',8'-pentaen-17'-yl]-4-hydroxy-2-butenoic acid lactone,
 3-[3'-sec.-butoxy-17' β -hydroxyestra-1',3',5'(10'),6',8'-pentaen-17'-yl]-4-hydroxy-2-butenoic acid lactone,
 3-[3'-cyclohexyloxy-17' β -hydroxyestra-1',3',5'(10'),6',8'-pentaen-17'-yl]-4-hydroxy-2-butenoic acid lactone.

(B) Sodium borohydride (27 g.) is added by portions over a period of 20 minutes to a suspension of 3-[7' α ,8'-epoxy-17' β -hydroxy-3'-methoxyestra-1',3',5'(10')-trien-17'-yl]-4,4-dihydroxy-2-butenoic acid lactone (9 g.), prepared as described in Example 6, in 360 ml. of methanol. After stirring at room temperature for 35 minutes, the methanol is evaporated. The residue is diluted with water and the mixture extracted with ether. The aqueous phase is acidified with a 10% solution of sulfuric acid. The resulting solid is collected, washed with water and dried. This solid is chromatographed on silica gel. The homogeneous fractions, indicated by thin layer chromatography, that are eluted with ethyl acetate-benzene (1:3), are combined and crystallized from methanol yielding the steroid lactone of Formula IV, 3-[7' α ,8'-epoxy-17' β -hydroxy-3'-methoxyestra-1',3',5'(10')-trien-17'-yl]-4-hydroxy-2-butenoic acid lactone, M.P. 137-143° C., $[\alpha]_D^{CHCl_3} = +101.7$.

In the same manner, 3-[7' α ,8'-epoxy-3',17'-dihydroxyestra-1',3',5'(10')-trien-17'-yl]-4,4-dihydroxy-2-butenoic acid lactone, 3-[3'-acetoxy-7' α ,8'-epoxy-17' β -hydroxyestra-1',3',5'(10')-trien-17'-yl]-4,4-dihydroxy-2-butenoic acid lactone, 3-[7' α ,8'-epoxy-17' β -hydroxy-3'-propionyl-oxoestra-1',3',5'(10')-trien-17'-yl]-4,4-dihydroxy-2-butenoic acid lactone and 3-[3'-n-butanoyloxy-7' α ,8'-epoxy-17' β -hydroxyestra-1',3',5'(10')-trien-17'-yl]-4,4-dihydroxy-2-butenoic acid lactone, prepared as described in Example 6, are reduced with sodium borohydride to the steroid lactone of Formula IV, 3-[7' α ,8'-epoxy-3'-17' β -dihydroxyestra-1',3',5'(10')-trien-17'-yl]-4-hydroxy-2-butenoic acid lactone.

In the same manner, an appropriate intermediate of Formula VI, prepared as described in Example 6, is reduced with sodium borohydride to the corresponding steroid lactone of Formula IV. In this manner, there are obtained the following steroid lactones of Formula IV:

3-[7' α ,8'-epoxy-3'-ethoxy-17' β -hydroxyestra-1',3',5'(10')-trien-17'-yl]-4-hydroxy-2-butenoic acid lactone,
 3-[7' α ,8'-epoxy-17' β -hydroxy-3'-propoxyestra-1',3',5' (10')-trien-17'-yl]-4-hydroxy-2-butenoic acid lactone,
 3-[7' α ,8'-epoxy-17' β -hydroxy-3'-isopropoxyestra-1',3',5' (10')-trien-17'-yl]-4-hydroxy-2-butenoic acid lactone,
 3-[3'-n-butoxy-7' α ,8'-epoxy-17' β -hydroxyestra-1',3',5'

(10')-trien-17'-yl]-4-hydroxy-2-butenoic acid lactone,
 3-[3'-sec.-butoxy-7' α ,8'-epoxy-17' β -hydroxyestra-1',3',5' (10')-trien-17'-yl]-4-hydroxy-2-butenoic acid lactone,
 3-[3'-cyclopentyloxy-7' α ,8'-epoxy-17' β -hydroxyestra-1',3',5' (10')-trien-17'-yl]-4-hydroxy-2-butenoic acid lactone, and,
 3-[3'-cyclohexyloxy-7' α ,8'-epoxy-17' β -hydroxyestra-1',3',5' (10')-trien-17'-yl]-4-hydroxy-2-butenoic acid lactone.

(C) Sodium borohydride (56.5 g.) is added portionwise over a period of 30 minutes to a solution of the acylated intermediate of Formula VI, 4-acetoxy-4-hydroxy-3-[17' β -hydroxy-3'-methoxyestra-1',3',5'(10')-trien-17'-yl]-2-butenoic acid lactone, prepared as described in Example 7 (11.3 g.) in 1130 ml. of methanol. Stirring is continued for 45 minutes. The solvent is removed by distillation under reduced pressure. The residue is taken up in ether and water. The water layer is separated and washed with fresh ether, and then cooled to 0° C. Acidification of the water layer with 10% sulfuric acid yields a solid, which is collected and washed with water. The solid is recrystallized from methanol and methylene chloride-ether to yield 4-hydroxy-3-[17' β -hydroxy-3'-methoxyestra-1',3',5'(10')-trien-17'-yl]-2-butenoic acid lactone, M.P. 217-219° C., $[\alpha]_D^{CHCl_3} + 83.6$.

In the same manner, the acetylated intermediates of Formula VI, 4-acetoxy-4-hydroxy-3-[3'-acetoxy-17' β -hydroxyestra-1',3',5'(10')-trien-17'-yl]-2-butenoic acid lactone, 4-acetoxy-4-hydroxy-3-[17' β -hydroxy-3'-propionyloxyestra-1',3',5'(10')-trien-17'-yl]-2-butenoic acid lactone or 4-acetoxy-3-[3'-n-butanoyloxy-17' β -hydroxyestra-1',3',5'(10')-trien-17'-yl]-4-hydroxy-2-butenoic acid lactone, prepared as described in Example 7, are reduced with sodium borohydride to the steroid lactone, 4-hydroxy-3-[3',17' β -dihydroxyestra-1',3',5'(10')-trien-17'-yl]-2-butenoic acid lactone.

In the same manner, the acetylated intermediates of Formula VI, 4-acetoxy-4-hydroxy-3-[3'-acetoxy-17' β -hydroxyestra-1',3',5'(10'),6',8'-pentaen-17'-yl]-2-butenoic acid lactone, 4-acetoxy-4-hydroxy-3-[17' β -hydroxy-3'-propionyloxyestra-1',3',5'(10'),6',8'-pentaen-17'-yl]-2-butenoic acid lactone or 4-acetoxy-3-[3'-n-butanoyloxy-17' β -hydroxyestra-1',3',5'(10'),6',8'-pentaen-17'-yl]-4-hydroxy-2-butenoic acid lactone, prepared as described in Example 7, are reduced with sodium borohydride to the steroid lactone, 4-hydroxy-3-[3',17' β -dihydroxyestra-1',3',5'(10')-trien-17'-yl]-2-butenoic acid lactone.

In the same manner, the acetylated intermediates of Formula VI, 4-acetoxy-3-[3'-acetoxy-7' α ,8'-epoxy-17' β -hydroxyestra-1',3',5'(10')-trien-17'-yl]-4-hydroxy-2-butenoic acid lactone, 4-acetoxy-3-[7' α ,8'-epoxy-17' β -hydroxy-3'-propionyloxyestra-1',3',5'(10')-trien-17'-yl]-4-hydroxy-2-butenoic acid lactone or 4-acetoxy-3-[3'-n-butanoyloxy-7' α ,8'-epoxy-17'-hydroxyestra-1',3',5'(10')-trien-17'-yl]-4-hydroxy-2-butenoic acid lactone, prepared as described in Example 7, are reduced with sodium borohydride to the steroid lactone of Formula IV, 3-[7' α ,8'-epoxy-3',17' β -dihydroxyestra-1',3',5'(10')-trien-17'-yl]-4-hydroxy-2-butenoic acid lactone.

In the same manner, the remaining acetylated intermediates of Formula VI, described in Example 7, are reduced with sodium borohydride to their corresponding steroid lactones of this invention.

Example 9

By using the same procedure as described in Example 5, but substituting an equivalent amount of 4-hydroxy-3-[3',17'-dihydroxyestra-1',3',5'(10')-trien-17'-yl]-2-butenoic acid lactone, 4-hydroxy-3-[3',17'-dihydroxyestra-1',3',5'(10'),6',8'-pentaen-17'-yl]-2-butenoic acid lactone, or 3-[7' α ,8'-epoxy-3',17' β -dihydroxyestra-1',3',5'(10')-trien-17'-yl]-4-hydroxy-2-butenoic acid lactone for 7, α -epoxy-17 α -[3'-furyl]estra-1,3,5(10)-triene-3,17-diol, and using the appropriate aliphatic acyl anhy-

13

dride, acetic anhydride, propionic anhydride or butyric anhydride, the corresponding steroid lactones of this invention of Formulae II, III and IV in which R is an acyl group, as defined above, 3-[3'-acetoxy - 17' β - hydroxy-estra-1',3',5'(10')-trien - 17'-yl]-4-hydroxy - 2 - butenoic acid lactone, M.P. 221-223° C., $[\alpha]_D^{CHCl_3} +71^\circ$, 4-hydroxy-[17' β -hydroxy - 3'-propionyloxyestra-1',3',5'(10')-trien-17'-yl] - 2 - butenoic acid lactone, 3-[3'-n-butanoyloxy-17' β -hydroxyestra-1',3',5'(10') - trien-17'-yl]-4-hydroxy-2-butenoic acid lactone, 3-[3' - acetoxy-17' β -hydroxyestra-1',3',5'(10'),6',8' - pentaen - 17' - yl]-4-hydroxy-2-butenoic acid lactone, 4-hydroxy-[17' β -hydroxy-3'-propionyloxyestra-1',3',5'(10'),6',8' - pentaen-17'-yl]-2-butenoic acid lactone, 3-[3'-n - butanoyloxy-17' β -hydroxyestra-1',3',5'(10'),6',8' - pentaen - 17'-yl]-4-hydroxy-2-butenoic acid lactone, 3-[3'-acetoxy-7' α ,8'-epoxy-17' β -hydroxyestra-1',3',5'(10') - trien - 17'-yl]-4-hydroxy-2-butenoic acid lactone, 4-hydroxy-[7' α ,8'-epoxy-17' β -hydroxy - 3' - propionyloxyestra-1',3',5'(10')-trien-17'-yl]-2-butenoic acid lactone and 3-[3'-n-butanoyloxy-7' α ,8'-epoxy - 17' β - hydroxyestra-1',3',5'(10')-trien-17'-yl]-4-hydroxy-2-butenoic acid lactone, are obtained.

I claim:

1. A compound selected from those of the formulae

wherein R is selected from the group which consists of hydrogen, lower alkyl containing from 1 to 4 carbon atoms, cycloalkyl containing from 5 to 6 carbon atoms and acyl containing from 2 to 4 carbon atoms.

2. A compound selected from those of the formula

in which R is selected from the group which consists of hydrogen, alkyl containing from one to four carbon atoms, cycloalkyl containing from five to six carbon atoms and acyl containing from two to four carbon atoms.

14

3. A compound selected from those of the formula

15 in which R is selected from the group which consists of hydrogen, alkyl containing from one to four carbon atoms, cycloalkyl containing from five to six carbon atoms and acyl containing from two to four carbon atoms.

4. 3-[3' - cyclopentyloxy - 17' β - hydroxyestra-1',3',5'(10')-trien-17'-yl] - 4 - hydroxy - 2 - butenoic acid lactone, as claimed in claim 1.

5. 3-[7' α ,8' - epoxy - 17' β - hydroxy - 3' - methoxyestra-1',3',5'(10') - trien-17'-yl] - 4 - hydroxy-2-butenoic acid lactone.

25 6. 4-hydroxy - 3 - [17' β -hydroxy - 3' - methoxyestra-1',3',5'(10') - trien-17'-yl] - 2 - butenoic acid lactone, as claimed in claim 1.

7. 3-[3' - acetoxy - 17' β - hydroxyestra-1',3',5'(10')-trien-17'-yl]-4-hydroxy-2-butenoic acid lactone, as claimed

30 in claim 1.

8. A compound selected from those of the formula

45 wherein R is selected from the group which consists of hydrogen, alkyl containing from one to four carbon atoms, cycloalkyl containing from five to six carbon atoms and acyl containing from two to four carbon atoms; and R¹ is selected from the group which consists of hydrogen and acyl containing from two to four carbon atoms; R¹ being hydrogen when R is hydrogen.

9. 3-[7 α ,8'-epoxy - 17' β - hydroxy - 3' - methoxyestra-1',3',5'(10') - trien-17'-yl] - 4,4 - dihydroxy-2-butenoic acid lactone, as claimed in claim 8.

55 10. 3-[3'-cyclopentyloxy - 7 α ,8' - epoxy - 17' β -hydroxyestra-1',3',5'(10')-trien-17'-yl] - 4,4-dihydroxy-2-butenoic acid lactone, as claimed in claim 8.
